UNITED STATES PATENT OFFICE.

ROBERT H. ROARK, OF WACO, TEXAS, ASSIGNOR TO PERFECTION ICE SCORING MACHINE COMPANY, OF WACO, TEXAS, A CORPORATION OF TEXAS.

METHOD OF AND MEANS FOR SCORING ICE.

Application filed February 9, 1924. Serial No. 691,751.

To all whom it may concern:

Be it known that I, ROBERT H. ROARK, a citizen of the United States, residing at Waco, in the county of McLennan and State 5 of Texas, have invented a new and useful Method of and Means for Scoring Ice, of which the following is a specification.

This invention relates to the art of scoring ice, which is usually manufactured in the 10 form of comparatively large rectangular blocks, which must be separated into smaller pieces for the usual retail trade.

The machine described herein embodies the essential features of the structure disclosed in my application No. 584,075, of 15 which the present application is a continuation in part.

The invention has for its main object the provision of a novel method and mechanism, 20 whereby a block of ice may be scored longitudinally and transversely to define a plurality of units, any desired number of which may be easily broken off by the retail dealer, the scoring not only facilitating the division 25 of the block into smaller pieces which will be uniform and marketable, but also insuring the delivery of an accurately determined amount without requiring weighing.

A further object is the provision of a machine for this purpose which will be comparatively simple and inexpensive to manufacture and assemble, easy to control and operate, not likely to get out of order, and a general improvement in the art.

The invention embodies novel means for turning or tilting the block of ice after it 35 has been scored in one direction, so that it may pass between saws for scoring in another direction, the entire machine being power driven and consequently positive in operation, and the tilting mechanism for turning the block being automatically operated and thus requiring no direct attention.

To the attainment of the foregoing the 45 invention consists in the construction, combination and arrangement of parts to be hereinafter more fully described and claimed, it being understood, however, that the specific mechanism is merely an exemplification of 50 a preferred structure, and the right is reserved to make such changes as will increase the utility or adaptability of the device, and to make all variations or modifications which

will not depart from the salient features of the invention, or the scope of the appended 55 claims.

In the drawings:

Figure 1 is a side elevation of the machine. 60 Figure 2 is a plan view thereof, with parts shown in section.

Figure 3 is a vertical longitudinal section through the machine.

Figure 4 is a horizontal section taken on the line 4—4 of Figure 3.

Figure 5 is a side elevation showing the 65 tilting cage in discharge position with blocks of ice about to enter between the respective sets of scoring saws.

Figure 6 is a horizontal section on the line 6—6 of Figure 5, showing the blocks of 70 ice passing between the saws and the tilting cage in position to receive the next block.

Figure 7 is a side elevation of the rear part of the machine with the scoring cage 75 partially tilted.

Figure 8 is a horizontal section on the line 8—8 of Figure 7.

Figure 9 is a transverse section on the line 9—9 of Figure 7.

Figure 10 is a detail view of the chain 80 attachment for tilting the cage.

Figure 11 is a detail view of the lever on the cage with which the chain attachment operates.

Figure 12 is a side elevation of a modified 85 form of machine embodying my invention.

Referring more specifically to the drawings, I have shown my invention as comprising an elongated rectangular frame 10, which consists of any desired arrangement 90 of longitudinal and transverse main bars, and any desired number of upright or other auxiliary bars which may be found necessary to support the bearings and other elements of the mechanism. At the bottom of the frame 10 is a longitudinal track or floor 11, over which the blocks of ice A are guided while being scored. This floor extends from the entrance end 12 of the machine to a point approximately at the center of the 95 machine, and the block of ice lies on its side as it is conducted into the frame from any suitable conveyor or other means, not shown.

Journalized in suitable bearings at one side 105 of the entrance end of the machine are var-

tical shafts 13 and 14, which carry sprocket wheels 15 near their lower ends, about which is trained a feed chain 16, provided with one or more prongs or teeth 17, adapted to engage against the rear ends of successive blocks of ice for conducting them through the first part of the machine. The shaft 14 is driven by means of a sprocket wheel 18 secured to the shaft above the sprocket wheel 15, and connected by a sprocket chain 19 to a sprocket wheel 20 secured to a vertical shaft 21 suitably journaled near the center of the machine, and driven by means hereinafter described.

15 Each block of ice, as it is delivered to the feed chain 16, is conveyed thereby over the track or floor 11 between guide rails 22, and into engagement with scoring saws 23, secured to vertical shafts 24 at opposite sides 20 of the machine. As represented in Figures 1 to 11, inclusive, the block of ice A is conveyed into the machine in horizontal position and is scored centrally from end to end, but it will be obvious that additional scoring 25 saws may be provided if desired.

The shafts 24, which carry the scoring saws 23, are driven by means of a transverse shaft 25, which is operatively connected to the shafts 24 by bevel gearing 26, within the 30 respective housings 27. The transverse shaft 25 has a gear 28 secured thereto, which is operatively connected by a toothed belt 29 to a gear 30, secured on the shaft 31 of a motor M, of any suitable type. Suitable 35 guards 32 are preferably provided for the saws 23.

Located near the center of the machine is a tilting cage 33, which has one side and one end open and is adapted to receive the 40 successive blocks of ice after they leave the scoring saws 23, and to tilt the same through an angle of approximately 90° and to deliver them to other scoring saws, whereby they may be scored at right angles to the first scoring. The tilting cage 33 is provided with trunnions 34, journaled in the 45 sides of the frame, and one trunnion has a lever 35 secured thereto by means of which the cage is tilted. The location of the trunnions 34, with respect to the cage 33, is such that the cage has a normal tendency to rest by gravity in the position shown in Figure 1, ready to receive a block of ice as it is delivered from the saws 23 by the chain 16.

50 The lever 35 is actuated by means hereinafter described to tilt the cage 33 after the block of ice has been delivered thereto, so as to bring the block of ice into position to be delivered to a track or floor 36, which is in 55 the same horizontal plane with the track or floor 11, and between guide rails 37, where it is carried into contact with the rear scoring saws.

55 The means for effecting the tilting movement of the cage 33 includes a shaft 38 jour-

naled across the top of the frame and carrying a beveled gear 39, which meshes with a beveled gear 40 secured to the upper end of the shaft 21. Secured to the shaft 38 is a sprocket wheel 41, about which passes a 70 sprocket chain 42, which also passes about an idler sprocket 43, suitably journaled near the lower part of the frame. The chain 42 travels between the lever 35 and the adjacent side of the frame, and throughout a 75 portion of its length, as shown in Figure 10, the pivot pins 44, which connect the links of the chain, are extended at one side and support a series of links 45, which terminate at the forward end in a prong 46, sufficiently 80 spaced from the side of the chain 42 to form a seat within which the upper end of the lever 35 is received, as shown in Figure 1. As the forward travel of the chain continues, therefore, the lever 35 is carried downwardly, as shown in Figures 7 and 5, until the cage 33 is tilted through an angle of approximately 90°, and the block of ice is delivered in upright position. The cage is held in this position until the series of projecting pins 44 and links 45 pass away from the lever, and permit the cage to be restored by gravity to its normal position, as shown in Figure 1. The ratio of the gearing which 85 forms part of the transmission mechanism 90 is important, as the movement of the feed chain 16 and chain 42 must have such a relation that the successive blocks of ice will be conducted properly through the machine, the blocks being passed or forced by the 100 chains 16 into the cage 33 when the latter returns to horizontal position after being tilted.

Rear feed chains 47 are provided, which 105 have prongs 48 adapted to engage the block of ice as soon as the tilting movement is completed, and to carry the same rearwardly. These feed chains 47 also provide means for driving the shaft 21, being trained about sprocket wheels 49 on said shaft, and about sprocket wheels 50 secured to a vertical shaft 51 at the rear end of the machine. The shaft 51 is driven by a bevel gear 52 secured to its upper end, and in mesh with a bevel gear 53 secured to the end of a countershaft 54, which is driven by a spur gear 55, meshing with a pinion 56 secured to a transverse shaft 57. The shaft 57 is provided centrally with a gear 58, which is 110 driven by a toothed belt 59 from the motor shaft 31.

As the blocks of ice are carried through the remaining portion of the machine after being tilted, they are subjected to action by scoring saws 60, any number of which may be provided, on vertical shafts 61 arranged at opposite sides of the machine, and driven by means of bevel gears 62 secured to their upper ends, and in mesh with bevel driving gears 63, which are secured to the ends of 115 120 125 130

the transverse shaft 57, within the housings 64. Suitable guards 65 may be provided for the individual saws 60.

- In the modified form of the invention 5 shown in Figure 12, the block of ice A enters the frame 10^a in upright position, and is carried rearwardly by a pair of chains 66, which are trained about sprocket wheels 67, secured to the vertical shafts 68 and 69. 10 The block of ice is thus carried into contact with saws 70 mounted on shafts 71, which score the block transversely. The block is then delivered into the tilting cage 72, which is supported on trunnions 73, to one of which 15 is secured an upwardly extending lever arm 74. This lever arm is engageable at the proper time by a lug 75 carried by the chain 76, and the course of the chain is such that the cage 72 is tilted through an angle of 20 somewhat more than 90° to the position shown in dotted lines, and from that position the block is delivered onto the rearwardly and downwardly inclined tracks 77, along which the block is carried by gravity. 25 During this latter part of the course of the block through the machine, it is scored longitudinally by saws 78, which are secured to shafts 79, which extend in an upward and rearward direction. The various instrumentalities 30 may be driven in any convenient manner from the motor shaft 80. In the arrangement of gearing, which is shown in Figure 12, as an example, the shafts 79 are connected by bevel gearing 81 to a shaft 82 35 extending transversely across the rear part of the machine, and driven by a belt 83, or the like, from a pulley 84 mounted on the shaft 80. The shaft 82 is connected by suitable belting 85 to the shaft 86, so as to drive the latter, and the saw shafts 71 are driven through the medium of a bevel gear connection 81 with the shaft 86. The shaft 68 is driven from a transverse shaft 88, connected as by belting 89 with the shaft 86. 40 The chain 76, which passes at its upper end over the sprocket wheel 90 mounted on a transverse shaft 91, is positively driven from, and in timed relation with the shaft 69, the shaft 91 being provided with a bevel gear 92 which meshes with a bevel gear 93 on the shaft 69, so that the cage 72 will be 45 in proper position to receive the block of ice as it is delivered from the feed chains 66. 50 From the foregoing description, considered in connection with the accompanying drawings, it will be apparent that I have provided a simply constructed and rapidly operating machine, which will accurately 55 score or groove blocks of ice, both longitudinally and transversely while they are carried through the machine, the entire mechanism being driven automatically, and being positive in its operation. Attention is also 60 called to the fact that ample means is provided for shifting the block automatically 65

from one position to another, during its progress through the machine. This shifting means, as has been previously noted, is so constructed and arranged that it operates in timed relation with the feed chains, so 70 that the tilting operation commences at the proper time after the block of ice has been delivered to the cage. Owing to the simplicity of the construction, and the comparative fewness of parts, it is apparent that there is 75 little to get out of order, so that the machine can be used economically for a long time.

It is obvious that the machine may be arranged so as to present the block of ice in horizontal position to the first set of saws, and in vertical position to the second set of saws, as shown in Figures 1 to 11, or the block of ice may be scored in the reverse order, as illustrated in Figure 12. The 80 block of ice may be positively conveyed by power means through its entire course through the machine, as illustrated in Figures 1 to 11, or the latter half of the movement of the block through the machine may be effected by gravity down an inclined plane, as shown in Figure 12, during which gravitational movement it is scored by the 85 second set of saws 78.

A particularly distinctive feature of this 90 invention lies in the fact that the general 95 course or direction of the block of ice through the machine is not changed, but it is carried in the same general direction while its position is altered, so that the longitudinal and transverse scoring are effected 100 during the process.

What is claimed is:

1. The herein described method which consists in moving a block of ice and simultaneously scoring the sides thereof in one direction, tilting the block in a vertical plane through an arc of substantially 90°, and subsequently moving the block and simultaneously scoring the sides thereof in a direction transverse to the first scoring, without changing the course of direction of movement of said block.

2. The herein described method, which consists in moving a block of ice in one direction and simultaneously scoring the sides thereof, tilting the block in a vertical plane to a position at approximately right angles to its former position, then moving the block in the changed position, and simultaneously 115 scoring the sides thereof transverse to the first scoring, the block being moved in the same general direction throughout the operation.

3. The herein described method which consists in moving a block of ice in one direction and simultaneously scoring the sides thereof, tilting the block to an upright position through an arc of substantially 90°, and while in the upright position applying 125 power driven means to the block to posi- 130

- tively advance the block in the same general direction and simultaneously causing the scoring of the block in a direction transverse to the first scoring.
5. 4. The herein described method, which consists in moving a block of ice along a track in one direction and simultaneously scoring the sides thereof, automatically tilting the block at the completion of the first 10 scoring through an arc of substantially 90°, and without changing the general direction of movement nor changing the elevation of the lower surface of the block, applying power driven means to the block to positively 15 advance the same and simultaneously scoring the block in a direction transverse to the first scoring.
5. In an ice-scoring machine, the combination with means for feeding a block of ice 20 and scoring it in one direction, means for receiving the block of ice from said scoring means, means for tilting the block of ice so as to change it to a position substantially at right angles to its first position, means for 25 moving said block in its changed position in the same general direction, and means for scoring said block in a direction at right angles to the first scoring.
6. An ice-scoring machine comprising a 30 pair of horizontally disposed rotating saws, means for feeding a block of ice between said saws, means for tilting the block in a vertical plane through an arc of substantially 90°, other rotating saws between which the 35 block passes after being tilted, and means for moving said block between said other saws in the same general direction.
7. In an ice-scoring machine, two sets of 40 rotary saws, and means between said sets for tilting a block of ice in a vertical plane from a horizontal to an upright position subsequent to its passage between one set of saws and prior to its passage between the other set, without changing the general direction of movement of said block.
8. In an ice-scoring machine, a guide 45 track at the entrance end, horizontal rotary saws, means for feeding a block of ice along the track and between said saws, means for tilting the block in a vertical plane for turning it to an upright position, and a second set of horizontal saws between which the block passes subsequent to tilting, said block being movable through the second set of saws without changing the general direction of movement thereof.
9. In an ice-scoring machine, guide means 50 at the entrance end, horizontal rotary saws thereabove, means for conducting a block of ice along said guide means between the saws, means for subsequently tilting the block through an arc of substantially 90°, a horizontal guide track at the outlet end onto which the block passes from the tilting 55 means without changing its general direc-
- tion of movement, and a set of horizontal saws above said horizontal track between which the block passes.
10. In an ice-scoring machine, guide means at the entrance end, scoring saws above said 70 guide means, means for moving a block of ice along the guide means, a tilting cage receiving the block subsequent to its passage between said saws, means for tilting said cage for turning the block through an arc of substantially 90°, and scoring saws at the outlet end between which the block passes subsequent to being tilted.
11. In an ice-scoring machine, guide means at the entrance end, scoring saws above said 80 guide means, means for feeding blocks of ice along the guides between the saws, a tilting cage receiving the successive blocks subsequent to their passage between said saws, means for tilting said cage at intervals for turning the blocks through an arc of substantially 90°, scoring saws at the outlet end between which the blocks pass subsequent to being tilted, and power driven means for feeding the blocks between the second named 85 saws.
12. In an ice-scoring machine, guide means at the entrance end, scoring saws above said 90 guide means, a tilting cage receiving the block subsequent to its passage between said saws, means for tilting said cage at intervals for turning the block through an arc of substantially 90°, scoring saws at the outlet end between which the block passes subsequent to being tilted, power operated 95 means for feeding the block between the first named saws and into the cage, and power driven means for engaging the block as the cage completes its movement, and for feeding said block between the second set of saws.
13. In an ice-scoring machine, guide means at the entrance end, horizontally rotary saws thereabove, a tilting cage having one end and one side open, means for passing a block of ice between said saws and into said cage, guide means at the outlet end, rotary saws above said outlet guide means, and means for tilting the cage to discharge the block in a different position onto said outlet guide means.
14. In an ice-scoring machine, guide means at the entrance end, horizontal rotary saws thereabove, a tilting cage, means for passing a block of ice between said saws and into said cage, guide means at the outlet end in the same horizontal plane with the first mentioned guide means, rotary saws above said outlet guide means, means for tilting the cage to discharge the block onto said outlet guide means, and power driven means for feeding the block between the second named 110 saws.
15. In an ice-scoring machine, means for scoring the ice in one direction, a tilting cage, means for conducting the ice from said 115

scoring means into said cage, and means for tilting the cage, consisting of a lever carried thereby, and a movable power driven element engaging the lever at a predetermined time.

16. In an ice-scoring machine, means for scoring the ice in one direction, a tilting cage, means for conducting a block of ice from the said scoring means into the cage, and means for tilting the cage to change the position of the block of ice, consisting of a lever carried thereby, a power driven sprocket chain, and an element on said chain engageable with said lever.

17. In an ice-scoring machine, means for scoring the block of ice in one direction, a tilting frame normally in upright position, means for conducting the block of ice from the said scoring means into said frame, an element carried by said frame, and trip means engageable with said element to tilt said frame with the block of ice therein.

18. In an ice-scoring machine, two sets of similarly arranged scoring saws, a tilting cage journaled between the sets and operating in a vertical plane, power driven feed means for passing a block of ice between one

set of saws into the cage, a trip mechanism associated with the cage and driven in timed relation to the feed means for tilting the cage to turn the block through an arc of substantially 90°, and means for passing the block between the other set of saws.

19. In an ice-scoring machine, guide means at the entrance end, rotary upright shafts carrying saws above said guide means, a tilting cage at the intermediate portion of the machine, feed chains for passing a block of ice between said saws into the cage, guide means at the outlet end of the machine, shafts arranged at right angles to said outlet guide means and extending upwardly, scoring saws on said last named shafts, means for driving all of said shafts and said feed chain simultaneously, a sprocket wheel driven from one of said shafts, a chain driven from said sprocket wheel carrying a lateral extension, and a lever on the cage in the path of movement of said lateral extension, whereby the cage is tilted.

In testimony that I claim the foregoing as my own, I have hereto affixed my signature.

ROBERT H. ROARK.
